UNITED STATES PATENT OFFICE

SAMUEL A. OTT, OF FORT STOCKTON, TEXAS.

BAG-HOLDER.

1,070,169.

Specification of Letters Patent. Patented Aug. 12, 1913.

Application filed March 6, 1913. Serial No. 752,334.

To all whom it may concern:

Be it known that I, SAMUEL A. OTT, a citizen of the United States, and a resident of Fort Stockton, in the county of Pecos and 5 State of Texas, have made certain new and useful Improvements in Bag-Holders, of which the following is a specification.

My invention relates to improvements in paper bag holders, and has for its object to 10 provide a device in which either a single unit may be employed or a series of units superposed one above or adjacent the other, the said units being preferably arranged in sets of various sizes of bags whereby bags 15 of practically all sizes from the largest to the smallest are conveniently placed and accessible in grocery and other stores, the bags in each holder being yieldingly retained in place, but readily removable when circumstances may require.

My invention consists in certain novel features of construction, arrangements and combinations of parts as will be hereinafter fully described and pointed out in the 25 claims, reference being had to the accompanying drawing in which,

Figure 1 is a front elevation of my improvement; Fig. 2 is a side elevation of same; and, Fig. 3 is a perspective view as in 30 use.

In carrying out my invention I preferably use a single piece of wire of the desired size; the wire is bent to the form shown in Fig. 1, that is, the side wires A are secured to the 35 base board B near the lower end by staples C; the wires A extend upwardly a slight distance lying against the base board and then bulge outwardly forming a breast, as at A'; they are then converged and twisted to 40 gether as at A², then spread outwardly again and curve backwardly to the baseboard B where they are secured to said board by staples C'; they are then curved upwardly, forwardly and downwardly as at A³, the 45 extreme ends A⁴ being turned outwardly so as to offer no obstruction to the entrance of a pack of bags. The wires A below where they are secured to the base board B, are bent at substantially right angles and project forwardly to form the base bars A⁵; they are again bent at angles and extending 50 upwardly where after being bent into coils A⁶ extend again upwardly and then laterally and rearwardly forming side retaining arms A⁷, said arms being formed by twisting the wire around itself and having

a straight portion within the twists which extends across from side to side to form a support A⁸ for the front portion of the bags within the holder, the coils A⁶ forcing said cross bar A⁸ and the side arms toward the 60 baseboard.

The lower edges of the bags D rest on the base wires A⁶ and the lower portion of the package of bags are yieldingly held against the back bars fastened to the baseboard by the action of the coils, the cross bar A⁸, and the side bars A⁷, preventing the bags from slipping sidewise off the baseboard B.

As shown, the bags are placed in the 70 holder the lower edges resting on the base wires or members A⁶ and the central portions of the bags rest against the bulged or breast portions A', the bags resting against said breast; the upper ends of the bags are 75 inserted under the turned over upper ends of the wires which form retaining hooks; it will be found preferable to cut out a portion of the front well of each bag at its upper end, as shown at D'. The reason for doing 80 this is to permit the forefinger of a person to be placed within the bag and by placing the thumb against the face of the bag permit a single bag to be pulled downwardly away from the hooks, and then upwardly out of 85 the lower holding portion, leaving the rest of the fingers free to be inserted in the mouth of the bag to open the same and have it ready for use; it is, of course, not absolutely necessary to cut out all bags, but it 90 will be readily seen that such arrangement renders it absolutely certain that only one bag at a time will be pulled out.

The proportions of my holder may of course be varied and the construction and 95 arrangement of some of the parts may be slightly changed without departing from the scope of my invention, as for instance, the metal parts may be made of sheet metal having the requisite resiliency to insure its proper and positive action. It will be noticed that the breast portion throws the upper portion of the bag which is to be handled first, outwardly to be within ready reach of the person without the hand coming in contact with the lower portion of the 100 holder.

My holder can be secured to a baseboard, store shelves, counters, or any other convenient place and may be made in various 110 sizes placed one above the other or side by side, or any arrangement desired.

The lower portion of the holder with the cross bar A⁸ and the side members or arm A⁷ form a pocket or cage for retaining the bags in place and in a flat condition. Instead of the two hooks A⁸ one could be used if desired though the use of two hold the bags in better shape while in the holder. The baseboard might be dispensed with and the holder suspended from wires by the hooks A⁸ if so desired.

I claim:

1. A bag holder comprising a resilient pocket or cage-like lower member having rearwardly projecting side arms, a back member having an intermediate bulged breast portion, and forwardly projecting curved overhanging hooks at its upper end.
2. In a bag holder the combination with a suitable base, of a holding device consisting of a single piece of wire bent to form a resilient pocket or cage-like member at its lower end, an intermediate bulged or breast portion, and forwardly projecting curved overhanging hooks at its upper end.
3. A bag holder comprising a resilient

pocket or cage-like lower portion, said lower portion consisting of back bars, horizontal lower bars for the bags to rest on, resilient vertical front bars, a cross bar bridging the vertical bars and extending laterally beyond the vertical front bars, side arms projecting rearwardly from the lateral projections, the back bars having an intermediate bulged or breast portion, the upper ends of the back bars being bent outwardly and downwardly to form overhanging hooks to retain the upper ends of the bags.

4. A bag holder comprising a resilient pocket or cage-like lower portion, back bars bulged outwardly intermediate its upper and lower ends and then converging to form a single longitudinal member, then diverging upwardly and having the upper ends bent over and forwardly to form overhanging hooks.

SAMUEL A. OTT.
